MARTIN HEUSY, OF BURLINGTON, OHIO.

Letters Patent No. 91,628, dated June 22, 1869.

IMPROVED DEVICE FOR CLEANING SAUSAGE-CASES.

The Schedule referred to in these Letters Patent and making part of the same.

To all whom it may concern:

Be it known that I, MARTIN HEUSY, of Burlington, in the county of Fulton, and State of Ohio, have invented a new and improved Device for Cleaning Sausage-Cases; and I do hereby declare that the following is a full, clear, and exact description thereof, which will enable others skilled in the art to make and use the same, reference being had to the accompanying drawing, forming part of this specification, in which—

Figure 1 represents a vertical transverse section of my improved machine.

Figure 2 is a plan or top view, on an enlarged scale, of the same.

Similar letters of reference indicate corresponding parts.

This invention relates to a new apparatus for cleaning the intestines used for sausage-cases, and is to supersede the ordinary scraping-method, by means of knives or sticks heretofore employed.

The invention consists in the use of a blade, or metal plate, A, which is secured to a U-shaped bar, or frame, B, the ends of which are pivoted to a platform, C.

The blade A forms the middle or front side of the frame B, and may, in suitable manner, be fastened to the same.

The ends of the frame A, are, by pins a, pivoted to ears b, that project from the platform.

The platform is placed upon an inclined bed, or otherwise in an inclined position, near a tub, D.

The intestines, which have first to be turned, are drawn through, between the blade and the platform, by one hand, the other hand pressing gently upon the blade.

The blade will then thoroughly scrape and clean that side of the cases exposed to its action.

When one side has been cleaned, the case is allowed to slip down on the platform, and is then drawn through once more, with its other face exposed to the blade.

Having thus described my invention,

What I claim as new, and desire to secure by Letters Patent, is—

As a new article of manufacture, a device for cleaning sausage-cases, made and operating substantially as herein shown and described.

MARTIN HEUSY.
